DESIGN.

—
H. HUNT.

CARPET.

No. 15,585.

Patented Dec. 2, 1884.

UNITED STATES PATENT OFFICE.

HENRY HUNT, OF GREENVILLE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 15,585, dated December 2, 1884.

Application filed August 8, 1884. Term of patent 3½ years.

To all whom it may concern.

Be it known that I, HENRY HUNT, of Greenville, New Jersey, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures, herein specifically shown and claimed.

The accompanying photograph is a face view of a carpet showing my new design.

15 The figure A is the large symmetrical figure in the upper center of the photograph. It has drooping-leaf forms at its lower part and two oblong-leaf forms on each side. The figure ends below with the central scalloped figure having five pendent scallops, and it terminates above with the small five-pointed central cap shown in the photograph. It is distinct in itself and separable from the rest of the design.

25 The figure B is a stem figure half encircling the figure A on the right, and bearing flower and leaf figures that are largely symmetrical, a leaf figure above, a large flower figure below, a bell-shaped flower below that, and blossoms at the end. The figure begins at or near the upper edge of the figure A, just to the right of the median line of that figure, and it is distinct and separable from it, although the two figures have a common boundary-line for a minute distance.

35 The figure C is the figure B reversed, half encircling the figure A on the left, and beginning at the lower edge of figure A, just to the left of the median line of that figure, similarly to the figure B. The figures B and C wholly 40 encircle the figure A, and the three figures together form a distinct and complete group, occupying the upper half of the photograph.

The figure D is the large symmetrical figure shown in the lower center of the photograph. 45 It has three blossom-clusters at its crest, a central oval-leaf figure at each side, below that toward the base a drooping-leaf figure on each side, and at the base itself a small five-scalloped pendant whose outline limits the figure 50 D at that end. The figure is distinct and separable from the rest of the design.

The figure E is a stem-like figure, half encircling the figure D below it and bearing various flower and leaf figures, generally symmetrical. The figure begins with the large cup-shaped flower figure directly to the right of figure D, and below the three-lobed corolla of that flower, forming the boundary-line of figure E on the right. Along the stem toward the left is a central flower, then a leaf mass, then a long leaf and blossoms, and the figure terminates in a recurring stem having small leaves and twigs. One of these touches the figure D at the base of that figure, the boundary-line of the two figures being coincident for a short distance, but 65 without any interblending of the figures.

The figure K is a stem-like figure, like the figure E in most part, reversed, and half encircling the figure D above that figure. On the left it is bounded by the outline of the three-lobed corolla at the base of the large cup-shaped flower. The figures D, E, and K form a group distinct and separable from the rest of the design, and that occupies the lower part of the photograph.

75 The figure F is shown partly at the right center of the photograph and partly at the left upper and lower corners. It is a large symmetrical figure. It has an ornamented central figure, in general form rectangular, with a 80 double spiral figure on each side. On each side is a conical figure. Above and below are two inwardly-drooping leaf figures bearing between them an arch of small oval figures having a scalloped border outside of them. This 85 scallop forms the boundary-line of the figure above and below. The figure is complete and separable from the rest of the design.

The figure G is a small stem figure, shown mostly at the lower right edge of the photograph. It has a large leaf figure, above that to the left a drooping leaf, below it to the right a sprig, and another above it to the right. The latter sprig approaches the figure F, and appears to have for a minute distance a boundary-line coincident with that of the figure F; but the figures do not interblend. The same thing is true of the scrolled angular stem portions of the figure G in the lower part of that figure, where they approach the figure E on the left 90 and the figure H below.

The figure H is shown partly at the left cen-

ter of the photograph and partly at the right upper and lower corners. It is a large symmetrical figure. Its boundary-line above, which is its base, is formed by five small scroll figures, the figure H including nothing above their upper boundary-line. Below this is a triangular center with an outline leaf on each side. Below this is a large heart-shaped figure with leaf figures on each side, and terminating below in two slightly-recurved leaf-like figures which touch each other below and then slightly separate. The boundary of these leaf-like figures is the boundary of the figure H below.

15 The figure J is a small stem figure, shown mostly at the lower left edge of the photograph. It has a large open leaf below, a flower figure to the left of that, and a stem with small branching leaves and twigs above it. On the left above, this figure approaches to the figure H, and on the right above to the figure K, and in each case there is for a minute distance a boundary-line common to the two adjacent figures; but they do not interblend in either case.

25 Through the peculiar positions of the stem figures G and J the figures D, E, F, H, and K form a general group distinct and separable from the rest of the design.

30 1 claim—

30 1. The design for a carpet, consisting of the figure A, substantially as shown and described.

2. The design for a carpet, consisting of the figure B, substantially as shown and described.

3. The design for a carpet, consisting of the figures A and B, substantially as shown and described.

4. The design for a carpet, consisting of the figures A, B, and C, substantially as shown and described.
5. The design for a carpet, consisting of the figures B and C, substantially as shown and described.
6. The design for a carpet, consisting of the figure D, substantially as shown and described.
7. The design for a carpet, consisting of the figure E, substantially as shown and described.
8. The design for a carpet, consisting of the figures D and E, substantially as shown and described.
9. The design for a carpet, consisting of the figures D, E, and K, substantially as shown and described.
10. The design for a carpet, consisting of the figures E and K, substantially as shown and described.
11. The design for a carpet, consisting of the figure F, substantially as shown and described.
12. The design for a carpet, consisting of the figures H and J, substantially as shown and described.
13. The design for a carpet, consisting of the figures D, E, F, G, H, J, and K, substantially as shown and described.
14. The design for a carpet, consisting of the figures A, B, C, D, E, F, G, H, J, and K, substantially as shown and described.

HENRY HUNT.
